HAIR CURLER

Samuel Freeman, New York, N. Y.

Application April 27, 1939, Serial No. 270,329

10 Claims. (Cl. 132—33)

My invention relates to a new and improved hair curler.

One of the objects of the invention is to provide a hair curler by means of which both ends of a curl are clamped between the body or shank of a bobby pin and two inturned gripping end-portions of said bobby pin.

Another object of the invention is to provide a combination of an improved curler and an improved bobby pin or clamping pin or other clamping device.

Another object of the invention is to provide improved means for curling the hair so as to form a uniform curl, in which all of the hairs are confined between the body of the bobby pin and the inturned gripping end-portions thereof.

Another object of the invention is to provide a device by means of which the bobby pin can be detachably assembled with the curler before the curler is operated.

Another object is to provide a device whereby the bobby pin can be detachably assembled with the curler, while the curler is open and also while the curler is closed.

Another object of the invention is to provide a device which will make it unnecessary to hold the bobby pin with one hand during the curling operation, even though the bobby pin is assembled with the curler.

Another object of the invention is to provide several embodiments which can be easily manufactured at low cost and which will be simple and convenient to use.

Other objects of the invention will be stated in the annexed description and drawing which illustrates several embodiments thereof.

Fig. 1 is a side elevation of one embodiment of the curler, assembled with the bobby pin. The curler is shown in the closed position.

Fig. 2 is a central vertical section of Fig. 1.

Fig. 3 is an end view at the line 3—3 of Fig. 1, with the representation of the spring omitted.

Fig. 4 is an enlarged detail view of a part of the device illustrated in Fig. 1.

Fig. 5 is a sectional view on the line 5—5 of Fig. 4, the representation of the spring also having been omitted in this view.

Fig. 6 is a top plan view of one of the clamping members which is used in another embodiment of the invention.

Fig. 7 and Fig. 8 are respectively sectional views on the lines 7—7 and 8—8 of Fig. 6.

Fig. 9 is a vertical sectional view of another

embodiment of the invention, part of the representation of the device having been omitted.

Fig. 10 is an elevation on the line 10—10 of Fig. 9.

Fig. 11 shows the assembly of an element of the general type illustrated in Fig. 6, together with a companion element of substantially the same construction.

Fig. 12 is a vertical sectional view of another embodiment.

Fig. 12a is a side elevation of one of the embodiments of the improved bobby pin which is used with the curling device.

It is well known to detachably assemble a conventional bobby pin with a hair-curling device or curler at one end of the curler, to form the curl on the curler, and then to slip the curl off the device together with the bobby pin, so that the wall of the curl is finally clamped between the legs of the bobby pin. In using devices of this type, one end of the curl is frequently not clamped between the legs of the bobby pin, and the hairs separated from the curl, thus producing an irregular curl.

For use with the improved device, I provide a bobby pin which is made of suitable resilient material such as metal or the like, and the shank of said bobby pin is provided with two inturned gripping end-portions. Several embodiments of this bobby pin are shown in my companion application filed on even date.

This improved bobby pin is detachably assembled with the curler so that the inturned gripping end-portions are separated from the shank of the bobby pin. After the curl has been completed, it is removed from the curling device in unison with the bobby pin. The inturned resilient gripping end-portions of the bobby pin then spring towards the shank of the bobby pin, so that the shank of the bobby pin overlies the entire wall of the curl and the wall of the curl is clamped at each end thereof between the shank of the bobby pin and the respective in-turned resilient gripping end-portion.

Referring to the embodiment shown in Figs. 1 and 2, said embodiment has semi-frusto-conical body members 1 and 2. These body members 1 and 2 have adjacent planar surfaces along which they contact when the device is closed. The body members 1 and 2 respectively have semi-conical recesses 1b and 2b at their front ends. At their rear ends the body members 1 and 2 are respectively provided with integral heads 7a and 7b and with integral arms 1a and 2a. When the body members 1 and 2 are in the

closed position shown in Fig. 2, their combined contour is generally frusto-conical, save for the heads $1a$ and $1b$. The combined recesses $1b$ and $2b$ then form a single conical recess. It is unnecessary to taper the members 1 and 2 and their shape could be semi-cylindrical or any other desired shape.

At its rear end the body member 1 is provided with a recess $1c$ which is of semi-conical shape save where it is interrupted by the arm $1a$. The body member 2 is provided with a corresponding recess $2c$. The arms $1a$ and $2a$ are of U-shaped cross-section, as shown in Fig. 5. However said arms can be of any desired shape. Said arms are connected by a pivot member 3 which may be of the rivet type. The shank of this pivot member 3 fits snugly in holes which are provided in the arm $2a$. The arm $1a$ is provided with slots 6 through which said shank passes, so that said arms are bodily movable towards each other and away from each other, in addition to being turnable relative to each other around the axis of pivot member 3 . The arm $2a$ may be provided with slots corresponding to the slots 6 . This relative bodily movement permits the planar clamping surfaces of the body members 1 and 2 to clamp the end of a curl of hair between said surfaces, since said additional relative body movement permits the planar clamping surfaces to contact fully with each other.

Generally speaking, the invention includes every form of device whereby the arms $1a$ and $2a$ can turn relative to each other around a predetermined axis and said arms can also move relative to each other independently of said turning movement.

Enough clearance is provided between the heads of the pivot pin 3 and the arms $1a$ and $2a$ so as to provide easy turning. The usual spring 4 urges the body members 1 and 2 towards each other until they normally contact fully along their adjacent planar surfaces.

The bobby pin 5 is made of resilient metal or other resilient material and it is provided with two integral inturned gripping-end portions. The tips of said end-portions normally touch or are very close to the shank of the pin 5 .

In the drawing herein, save for Fig. 12a, the inturned gripping end-portions of the bobby pin 5 are shown as temporarily sprung away from the shank of the pin. For further details of the bobby pin, reference is made to my companion application filed on even date.

It may be assumed that the bobby pin is located in a definite plane, this being the plane of the paper in Fig. 12a. The bobby pin is introduced between the separated members 1 and 2 , with the plane of the bobby pin parallel to the median plane of the device, which is indicated by the reference letter $1p$ in Fig. 3. When the device is closed, the planar clamping surfaces of members 1 and 2 clamp the tip of the lock of hair in said plane. The inturned end-portions of the bobby pin can then be located in the end recesses of one of the members 1 and 2 , such as the recesses $2b$ and $2c$, without bending or without substantially bending the shank of the bobby pin. It is merely necessary to temporarily spring the inturned end-portions of the bobby pin away from its shank. As later stated herein, the gripping end-portions can be sufficiently normally spaced from the shank so that the bobby pin can be assembled with the curler without bending or stressing any part of the bobby pin.

The end of the lock of hair is then clamped between the planar surfaces of the body members 1 and 2 . While the body members 1 and 2 are thus in clamping position, the curling device is turned around its own longitudinal axis so that the hair is wound spirally around the closed members 1 and 2 and the curl is formed between the outer wall of the closed curling device and the spaced shank of the bobby pin 5 .

While the curl is being formed, the curler can be turned with one hand and the bobby pin can be held against turning with the other hand. The hair will not contact with the shank of the bobby pin until the wall of the curl has a predetermined thickness. If the space between the shank of the bobby pin and the outer wall of the closed curler is sufficiently large, the wall of the curl will not contact with the shank of the bobby pin during the entire curling operation, and the device may be used in this manner. It is not necessary to hold the bobby pin with one hand. If the curler can turn freely relative to the bobby pin, the bobby pin will hang freely from the curler, while the curler is turned relative to the bobby pin. If the bobby pin tends to turn in unison with the curler, the turning of the curler will first turn the bobby pin in unison with the curler, until the bobby pin contacts with the lock of hair. This will prevent further turning of the bobby pin in unison with the curler. Hence it is one of the advantages of the improved device that it can be held at each end thereof by the operator. Likewise, the wall of the curler can be spaced from the shank of the bobby pin when the curl has been fully wound upon the curler, or the wall of the curl can be caused to contact with the bobby pin, at any time prior to the completion of the winding of the curl.

It is sufficient if the initial spacing between the shank of the bobby pin and the outer wall of the curler is large enough to enable the hair to enter said space. Further winding of the hair around the curler so as to increase the thickness of the wall of the curl will outwardly bend the resilient shank. The hair is wound in curl form around the curler fairly tightly, but with enough clearance between the curler and the inner wall of the curl so that the body members 1 and 2 can be slightly separated after the curl has been made. The bobby pin, assembled with the curl, can then be slipped longitudinally off the curler.

After the curl has been completed, the body members 1 and 2 are slightly separated, so that their planar clamping surfaces release the curl. The bobby pin is then turned around an axis parallel to its shank, and the bobby pin is also moved bodily in a direction perpendicular to its shank to a release position, until the entire bobby pin, including its gripping end-portions, is located in the space between said planar clamping surfaces, and the gripping end-portions spring back towards the shank, thus clamping each end of the curl between the shank and the respective gripping end-portion. The curl and the assembled bobby pin are then held in one hand, and the curler is slid longitudinally out of the curl from left to right (referring to Fig. 1) with the other hand, leaving the bobby pin in its clamping position on the curl. The curl is therefore effectively gripped at each end thereof by the bobby pin before the curler is separated from the curl and the bobby pin, and before there is any relative longitudinal movement between the curl and the bobby pin. The curler can be held

stationary, and the curl and the bobby pin can be slid off the curler when the bobby pin is in the release position, and it has clamped the ends of the curl.

In Fig. 2, one of the tips of the gripping end-portions extends to the inner ends of the associated recesses. This is not necessary, and both tips of the gripping end-portions can be spaced from the inner ends of the respective recesses. If desired, both tips can extend to the ends of the associated recesses.

If desired, the bobby pin can be snapped into the position shown in Fig. 2 while the curling device is closed. The method of manipulation is then the same as that previously described.

In the second embodiment of Figs. 6-8, the body members 8 and 9 have semi-cylindrical recesses like the recess 8b at their front ends, and semi-cylindrical recesses like the recess 9c at their rear ends, save where said rear recesses are interrupted by arms 8a. The embodiment of Fig. 11 corresponds to that of Fig. 6, save that the recesses are deeper in Fig. 6 than in Fig. 11. The arm 9a is provided with vertical slots 17 which correspond to the slot 6 and the pivot pin 18 corresponds to the pivot pin 3. The recesses 8b and 9b are equal, and the recesses 8c and 9c are also equal.

As shown in Fig. 6, the end recesses of the body members are much deeper than in the first embodiments of Figs. 1-5, and the length of each gripping end-portion of the bobby pin is almost equal to one-half the length of the shank, so that almost the entire wall of the curl is clamped between the shank and the gripping end-portions. If the hair is moistened prior to curling the same, and each curl is allowed to dry while it is thus clamped by an associated bobby pin, the dry hair retains the curled form. The curl can then be unrolled in order to remove the type of bobby pin shown in Fig. 6, and upon then releasing the dry curled lock of hair, it will naturally resume its curled shape. The length of each gripping end-portion may be any proportion of one-half the length of the shank.

By separating the body members, the bobby pin can be inserted between said body members, and the gripping end-portions of the bobby pin can be readily inserted in the end-recesses of one of the body members. The method of use is the same as that previously described.

The first two embodiments can be made by molding or die-casting the parts, which can be made of metal or any suitable plastic or the like. Said embodiments can also be made by screw-machine work.

The parts of the third embodiment of Figs. 9 and 10 can be made by a simple stamping process. This third embodiment comprises a pair of semi-cylindrical or tapered half-sleeves 10 and 11, which are connected turnably by the means previously illustrated. In this third embodiment the half-sleeves 10 and 11 can turn relative to each other about the pivot of half-sleeves 10 and 11 and they can also move bodily relative to each other in a non-turning movement as previously illustrated.

Semi-cylindrical or tapered outer half-sleeves 12 and 14 are provided with struck-out angular tongues 15 whose shanks fit snugly in suitable openings in the walls of the inner sleeves 10 and 11. The longitudinally bent portions of the tongues 15 are connected to the inner members 10 and 11 by means of solder or in any other suitable manner. The outer half-sleeves 12 and

14 are thus held permanently spaced from the inner half-sleeves 10 and 11. The outer half-sleeve 12 moves in unison with the corresponding inner half-sleeve 10 and the outer half-sleeve 14 moves in unison with the inner half-sleeve 11.

As shown in Fig. 10, the inner half-sleeves 10 and 11 may be slightly spaced from each other when the outer half-sleeves 12 and 14 contact along their adjacent clamping planar surfaces.

10 The adjacent planar surfaces of half-sleeves 10 and 11, and of 12 and 14, act as clamping surfaces. The clamping surfaces of half-sleeves 10 and 11 may contact when the clamping surfaces of half-sleeves 12 and 14 contact.

15 The bobby pin which is used with the embodiment of Fig. 9 may have the tips of its inturned gripping end-portions normally spaced from the shank of said bobby pin, when said bobby pin is in the normal unstressed condition.

20 The walls of the half-sleeves 12 and 14 may be very thin, as thin as $\frac{1}{2}$ of an inch. The normal distance between the shank of the bobby pin and the tip of its inturned end-portion may be $\frac{1}{2}$ of an inch or more. Hence it is possible to 25 assemble the bobby pin with one of the half-sleeves 12 and 14, when they have been separated, without springing the gripping end-portions away from the shank. The shank will then depend freely from the curler, and the shank will be bent away from the curler as soon as the wall 30 of the curl exceeds a predetermined thickness, which will exceed the normal distance between the shank of the bobby pin and the tips of its gripping end-portions.

35 Fig. 6 shows a bobby pin having its gripping end-portions provided with upstanding walls of curved or bow shape. When the resilient gripping end-portions are sprung away from the shank, the end-edges of the body members will contact with the median portions of said bows, when the bobby pin is assembled with the curler. Further lateral movement of the shank towards the curler-member will then be prevented, so that the shank will be held normally spaced 40 from the outer wall of the closed curling device. The shank shown in Fig. 6 will be bent laterally away from the outer wall of the closed curling device, if the wall of the curl is of sufficient thickness.

45 The length of the curl may be equal to the length of the body of the curler, or less than such length.

50 This device therefore makes it possible to make 55 curls of any length, and much longer than has heretofore been possible with former devices in which an ordinary bobby pin was detachably mounted in a curler prior to the commencement of the curling operation.

The embodiment of Fig. 12 comprises an outer sleeve 20 which is made of fabric or other suitable bendable or flexible material. Rigid inserts 24 are located at the ends of said sleeve 20 and said inserts are suitably connected to the ends 60 of said sleeve. A rigid clamping bar 21 is pivotally connected at 22 to the insert 24 and to the corresponding portion of the sleeve 20. This clamping bar 21 may or may not have a spring.

A compression spring 27 maintains the cylinder 20 in the normal shape shown in Fig. 12, in which its outer surface is smooth. The bobby pin can be readily slipped into the position shown in Fig. 12 when the inserts 24 are pushed towards each other so as to diminish the effective 70 length of the sleeve 20. The inserts 24 are pro-

vided with integral fingerhold projections 23. Annular grooves 26 are thus provided in the inserts 24 for receiving the inturned ends of the bobby pin. The curl is made while the device has the normal shape shown in Fig. 12. The length of the sleeve 20 is then diminished by pushing the inserts 24 towards each other, so as to release the gripping end-portions of the bobby pin from the grooves 26. The curler can then be separated from the curl and the bobby pin. The member 20 can consist of conventional telescopic sleeves.

Fig. 12a shows a bobby pin having a shank 5 and having gripping end-portions provided with flat walls W which are substantially perpendicular to the shank 5. This bobby pin can be made out of resilient wire whose cross-section is circular or rectangular or of any other suitable shape. As shown in Fig. 6 the walls W can be outwardly bowed instead of being flat or planar.

Fig. 12a shows the tips of the gripping end-portions abutting the shank 5. Since a curl has substantial thickness, this contact is not necessary and the tips of the gripping end-portions may be normally spaced from the bobby pin when it is in the unstressed or normal shape.

I have shown preferred embodiments of my invention but it is clear that numerous changes and omissions can be made without departing from its spirit.

While I prefer to use a bobby pin or holding member which is made of resilient material, the invention is not to be limited thereto because the holding members shown in Fig. 12a and in the other figures can be made of wire strip or the like which is bendable but which is not resilient. Such non-resilient clamping members can be made in the normal shape illustrated in Figs. 6 and 12a, for example, and they can be used in the manner previously stated, save that it would be necessary to bend the gripping end-portions towards the shank, in order to clamp the curl. In each of the embodiments the bobby pin can be released from the curler without substantially bending the inturned ends of the bobby pin relative to its shank. This is a substantial advantage because although these bobby pins are made of resilient material, they are permanently deformed out of normal shape if said inturned ends are bent too much relative to the shank.

While I have described the formation of a spiral curl, the invention is not limited to the formation of such curl.

In the embodiment of Figs. 1-4, the two body members 1 and 2 operate to clamp the end of the lock of hair between said body members so that it is unnecessary to provide a supplemental clamping member. It is well known to provide a conventional type of curler having a sleeve-like body and a clamping member which is pivotally connected to said sleeve-like body, and the invention is not limited to a curler of any particular construction.

In each of the embodiments herein described, the curler is shaped so as to detachably hold the bobby pin assembled with the curler, by means of the inturned ends of the bobby pin. Likewise, the shank of the bobby pin, or a sufficient portion thereof, is held normally spaced from the curler, so that hair can be introduced between the shank and the curler. The curler is constructed so that it can be manipulated to release the bobby pin, without substantially bending the shank of the bobby pin.

I claim:

1. In combination, a curling device and a clamping device, said clamping device having a shank which has inturned ends, said curling device having two parts which are capable of movement relative to each other, said parts being shaped to releasably hold the clamping device at the inner faces of said inturned ends, said two parts being movable to a position in which said clamping device is releasable from said curling device without substantially bending said shank, said curling device being turnable relative to the assembled clamping device, when said clamping device is held as aforesaid.
2. In combination, a curling device and a clamping device having a shank which has inturned ends, said curling device having two parts which are pivotally connected to each other so that said two parts can be moved away from each other and towards each other, said parts being shaped so that said clamping device can be held at the inner faces of its inturned ends by either of said parts when said parts are separated from each other and without substantially bending said shank or said inturned ends, said curling device being turnable relative to the assembled clamping device.
3. In combination, a curling device and a clamping device, said clamping device having a shank which has inturned ends, said curling device comprising two parts which are pivotally connected, each of said parts having end recesses adapted to detachably receive said inturned ends, said curling device being turnable relative to the assembled clamping device.
4. A hair-curling device comprising two parts which are movable towards each other and away from each other, said parts having recesses which are shaped to detachably receive the inturned ends of the shank of a clamping device, said hair-curling device being turnable relative to the assembled clamping device.
5. A curling device comprising two parts which are pivotally connected to each other, said parts having adjacent clamping surfaces, said parts being shaped to detachably receive the inturned ends of the shank of a clamping device, said curling device being turnable relative to the assembled clamping device.
6. A curling device comprising a first member having recesses at its ends which are shaped to detachably and turnably receive the inturned ends of the shank of a hair-clamping device, and a clamping member associated with said first member.
7. A curling device which has a holding member shaped to detachably and turnably hold the ends of a hair-clamping device so that said holding member can be turned relative to said hair-clamping device.
8. A curling device which has a holding member having recesses at the ends thereof, said recesses being shaped to detachably and turnably hold the ends of a hair-clamping device so that said holding member can be turned relative to said hair-clamping device.
9. In combination, a curling device, a resilient clamping device having a shank and an inturned end at each end of said shank, said curling device having two portions which are movable relative to each other and which are movable relative to each other to a predetermined holding position, said portions being shaped to hold said clamping device at its inturned ends when said portions are in said holding position, said por-

tions being movable to a second position in which said inturned ends can be released from said portions while maintaining said ends in in-turned position, said curling device being turnable relative to the shank when said portions are in holding position.

10. A curling device having two holding portions which are movable relative to each other, said holding portions being shaped to rotatably

5 grip the inturned ends of the shank of a hair-clamping device when said holding portions are in predetermined holding position, said holding portions being movable out of said holding position to a second position in which said hair-clamping device can be released from said curling device while maintaining said ends in in-turned shape.

SAMUEL FREEMAN.
